COOLING AND HUMIDIFYING SYSTEM

Agnew H. Bahnsen, Jr., and William W. Avera, Winston-Salem, N.C., assignors to The Bahnsen Company, Winston-Salem, N.C., a corporation of North Carolina

Application January 12, 1954, Serial No. 403,507

4 Claims. (Cl. 236—44)

This invention relates to a cooling and humidifying system which is particularly adapted for a textile weave room or other shop in which considerable lint, size or dirt is entrained in the air.

In air conditioning systems using outside air for cooling in the summer time, provisions are made to recirculate room air through the fans and humidifiers so that the desired room temperature can be maintained. These systems are designed such that the fan handles a constant air quantity which means that the recirculating dampers will modulate to the open position while the fresh air dampers will modulate to the closed position and vice versa. This feature is present in both the central station and wet duct type systems. The object of this particular arrangement is to reduce the steam consumption by the utilization of room air in cool weather. It has been found that the expected economy is not obtained in the case of air conditioning for weave rooms and other shops or mills in which considerable lint, size, and/or other dirt is entrained in the air as the cost of cleaning the screens or filters which cover the recirculated air opening offsets the savings due to a lower steam consumption.

An object of the present invention is to provide an air conditioning system for mill rooms, and especially for weave rooms which is more economical in operation than the prior systems. An object is to provide an efficient humidity and temperature control system which is characterized by an absence of any recirculation of the room air through a humidifier unit. An object is to provide a humidity and temperature control system for weave rooms in which there is no recirculation of room air and the introduction of fresh clean air is limited substantially to that which is employed for cooling to maintain a pre-selected maximum temperature.

More specifically, objects are to provide a process and equipment for controlling the humidity and temperature which are characterized by humidifiers within the room to maintain a desired relative humidity and a duct system and fan for introducing fresh air into the room, the quantity of fresh air so introduced being regulated by a room thermostat to that quantity required for evaporative cooling to maintain the room temperature below a selected value or to prevent back flow into the duct system when no cooling is required.

These and other objects and the advantages of the invention will be apparent from the following specification when taken with the accompanying drawings in which the two views are fragmentary and somewhat schematic plan views of weave rooms provided with humidity and temperature control systems embodying the invention.

2

In Fig. 1 of the drawings, the reference numeral 1 identifies the outside wall of a wave room which is completely closed except for outwardly opening louvers, not shown, for the venting of air from the room when outside air is introduced. Water is evaporated directly into the room air under control of a humidostat 2 to maintain a desired relative humidity within the room. As shown schematically, the humidifier units comprise atomizers 3 on a pipe line 4 which is supplied with water through a control device 5 that is regulated by any desired form of electric or compressed air control line 6 from the humidostat 2. The individual atomizers 3 are preferably arranged adjacent the outlets 7 of a duct 8 of a separate humidifier system 9 of the central station type. This auxiliary humidifier system may be of the type described and claimed in prior Patent No. 2,262,542, Agnew H. Bahnsen, Jr. and the air inlet to the system is within an entrance chamber 10 which is closed except for openings to the outside air which are provided with louvers 11 and 12 respectively, the louvers 11 being in front of a heater 13.

A multi-speed fan F is driven by a motor 14 to force air through the evaporator section 15 of the humidifier assembly, the central humidifying chamber and the eliminator plates 16 which serve to remove entrained drops of water from the moist air stream. A room thermostat 17 operates through control line 18 and a variable speed control device 19 to regulate the speed of fan 14 in accordance with the demand for cooling to prevent the temperature of the room air from rising above a preselected maximum value, and a branch control 18' extends from thermostat 17 to the operators 11' and 12' of the louvers 11 and 12 respectively to open the same progressively in accordance with the increasing fan speed.

Water is supplied to the evaporator section 15 through a modulating valve 20 in the pipe 21, the valve 20 being controlled through a line 20' by a duct thermostat 26 in series with an entrainment control hygrostat 27. The duct thermostat 26 is set to reduce the supply of water to the evaporators 15 when the duct temperature is decreasing and approaching the room dew point. A supervisory control is also imposed upon the water valve 20, namely a relay 22 is included in control line 20' to close the valve completely in the event that the fan motor 14 is de-energized through the starter 19, the relay 22 being of known electro-pneumatic type and energized through a control line 22' connected to contacts of the variable speed control motor starter 19.

So long as the temperature within the room is below the desired value, the central station system 9 is delivering only enough air for ventilation; this minimum air quantity produces a slight over-pressure in the duct 8 and prevents a reverse flow of room air into the duct. This feature eliminates a serious cleaning problem as a reverse flow of room air into the duct would deposit dirt within the duct. Although the relay 22 is energized, since electrical power is available at the motor starter 19 and the fan F is in operation, the water modulating valve 20 is closed or substantially closed by the duct thermostat 26 and entrainment control hygrostat 27; however these instruments are capable of opening the water valve 20 to full volume should their set points be exceeded. When the room temperature reaches the selected maximum value, the thermostat 17 operates through the variable

speed control 19 to increase the fan speed. At the same time, the room thermostat 17 operates through the control line 18' to start the opening of the louvers 11 and 12 to admit outside air to the entrance chamber 10. The water valve 20 is positioned to an appropriate degree by the dust thermostat 26 in response to fluctuations in temperature brought about by the louver movements and the steam coil. When control 19 is adjusted for maximum fan speed, louvers 11 and 12 are fully open, the water valve 20 will be wide open if the outside wet bulb temperature is above the duct thermostat 26 setting, and the air volume has reduced the entrainment to a point below the setting of the entrainment control 27.

A wet bulb thermostat 23 may be mounted at the outlet side of the eliminators 16 to open valve 24 in steam line 25 to heater 13. This arrangement allows more evaporation to take place in the washer chamber 9, thus reducing the load on the room evaporators. The setting of the wet bulb thermostat may be below the room dew point, therefore a dry bulb thermostat 26 must be provided to prevent condensation on the duct in the room. The duct thermostat 26 limits the amount of evaporation such that the resulting temperature is above the dew point of the room and condensation will not occur.

The variable fan speed may be obtained in different manners, for example by employing a variable speed mechanical or fluid drive between a constant speed motor and the fan or, as shown schematically, by employing a step-by-step control 19 between a current source S and the motor connections L to regulate the fan speed.

Advantages of the described system are economy in the operation of the system since there is no recirculation of room air through the central station humidifier system and therefore no necessity for a periodic cleaning of lint and dirt from the filters employed in the recirculation types of humidifiers, and economy through the use of variable speed fans to handle only a limited quantity of air in proportion to the heat load to be dissipated.

Many elements of the embodiment shown in Fig. 2 are or may be identical with those of Fig. 1 and are identified by like reference numerals but will not be described in detail. The major difference between the two systems is that the motor 14 which drives fan F of Fig. 2 may run at constant speed as the control of the quantity of fresh air introduced through duct 8 for room cooling is through regulation of the relative positions of exit louvers 28 and by-pass louvers 29 by the room thermostat 17. The common operator 30 for the louvers is energized by thermostat 17 through the control line 18, and the sets of louvers are so connected by a linkage 31 that the louvers 28 open as louvers 29 close, and vice versa.

The exit louvers 28 are a refinement of the system and may be omitted since, when the fresh air dampers are closed and the by-pass louvers 29 are fully open, i.e. when there is no demand for room cooling by the room thermostat 17, only such fresh air as leaks through the fresh air dampers flows through the duct 8 for ventilation of the room.

The operators 11', 12' of the sets of inlet louvers 11 and 12 respectively are controlled by room thermostat 17 and control line 18' through separate relays 32 and 33 in such manner that louvers 11 in front of heater 13 open during cold weather when a minimum amount of cooling is required and the louvers 12 open after the louvers 11 are fully open.

In the operation of this embodiment of the invention, the primary supply of moisture to the room air is through the atomizers 3 under control of the humidostat 2.

So long as the room temperature is below the pre-selected normal value, the outlet louvers 28 are closed and the by-pass louvers 29 are fully open, thereby returning substantially all air which passes through the auxiliary humidifier system back to the inlet fan F. The on-off control of modulating valve 20 in the water supply pipe 21 is established, as in the Fig. 1 system, by a relay 22

75 which is energized from the motor starter 19 to insure that the water supply will be cut off in the event of a failure of electrical power. If the water were not cut off upon a failure of the fan, there would be a back flow of spray from the fan inlet into the chamber 10. The motor 14 is preferably in operation to maintain a slight pressure in duct 8 to prevent room air from entering and depositing dirt in the duct. Upon a rise in room temperature, thermostat 17 operates through control line 18 progressively to close louvers 29 in accordance with the demand for cooling, and simultaneously to open the louvers 28 if such exit louvers are included in the system; and through control lines 18' to open the inlet louvers 11, 12.

15 The operation of the supervisory control elements, i.e. wet bulb thermostat 23, duct thermostat 26 and hygrostat 27, may be substantially as previously described or the wet bulb thermostat 23 may be omitted by imposing the control of valve 24 in the steam line to heater 13 upon the duct thermostat 26. The steam valve will work 20 in sequence with the water valve to maintain the duct temperature.

It is to be understood that it is not essential that a constant speed motor be employed in the Fig. 2 system in which the regulation of the fresh air introduced into the room is based upon a diverting of some of the available air back to the fan inlet, and that considerable economy 25 in power costs can be effected by employing a multispeed motor and controlling the motor speed in accordance with the demand for cooling. Furthermore, in place of

30 running fan F continuously at low speed to prevent room air from backing into duct 8 and depositing dirt, a separate small fan may be operated continuously in chamber 10 to prevent reverse flow of room air into the duct and the fan F need then be operated only as required for introducing fresh air into the room for evaporative cooling.

35 It is thus apparent that there is considerable latitude in the construction and operation of apparatus contemplated by the present invention and falling within the scope and spirit of the following claims.

40 We claim:

1. In a ventilating and humidifying system for a room, the combination with humidifying means within the room, and humidity responsive control means within the room for regulating the operation of said humidifying means to maintain a desired relative humidity within said room; of an auxiliary humidifier system of the central station type having a humidifier unit between outlet means opening into said room and inlet means communicating with the outside air, a continuously operating fan for drawing outside air through said inlet means and discharging it through said outlet means after passage through said humidifier unit a hygrostat at said outlet means, means controlled by said hygrostat to limit the water supplied to said humidifier unit to the quantity which is completely evaporated in the fresh air in transit to the room, and a modulating means actuated by a thermostatic control device within the room for regulating the quantity of outside air introduced into the room through said auxiliary humidifier system in accordance with the extent to which the room temperature exceeds the preselected value, said modulating means always maintaining at least a minimum flow of fresh air to said outlet means notwithstanding temperature conditions in the room thereby to maintain a slight overpressure in the ducts leading to said outlet means and preventing any back flow of room air into said outlet means.

2. In a ventilating and humidifying system, the invention as recited in claim 1, wherein said modulating means includes adjustable louvers in said inlet means of the auxiliary humidifier system.

3. In a ventilating and humidifying system, the invention as recited in claim 1, wherein said modulating means includes louvers at the outlet means of said auxiliary humidifier system and adjustable to regulate the relative quantity of air which is discharged into the

room and that which is recirculated through said auxiliary humidifier unit.

4. In a ventilating and humidifying system, the invention as recited in claim 1, in combination with a supplemental thermostatic control device at said outlet means, and heating means energized by said supplemental thermostatic control device for heating the air in transit through said central station humidifier unit to maintain the moist fresh air discharged into the weave room at a temperature above the dew point of the moist air already present within the weave room. 10
